UNITED STATES PATENT OFFICE.

GEORGE P. MORLOCK, OF PLYMOUTH, INDIANA.

SACK-SCALE.

SPECIFICATION forming part of Letters Patent No. 340,594, dated April 27, 1886.

Application filed January 26, 1886. Serial No. 189,823. (No model.)

To all whom it may concern:

Be it known that I, GEORGE P. MORLOCK, a citizen of the United States, residing at Plymouth, in the county of Marshall and State of Indiana, have invented certain new and useful Improvements in Grain-Meters; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to grain-meters; and it consists in details of construction and novel combinations of parts, more particularly hereinafter referred to, and pointed out in the claims.

In the annexed drawings, Figure 1 is a front view of a machine constructed in accordance with and adapted to carry out my invention. Fig. 2 is a plan view with parts broken away. Fig. 3 is a section on the line X X of Fig. 2 of the upper portions. Fig. 4 is a section of a similar part on the line Y Y of the same figure.

The frame is closed in on three sides by the sides A and back A', and is divided centrally by a vertical partition, A², forming two compartments, B B'. Levers C, pivoted on the inner sides of the compartments at c, are arranged in pairs, one for each compartment, as shown. The rear ends of each pair of the levers are united by a yoke, C', having a rearwardly-projecting arm, c'. Frames or stirrup-platforms D depend from the inner ends of the pairs of levers, and are of such a length that when the one rests on the bottom of the frame the other is at a distance above such bottom. These platforms are intended to support grain-receptacles, which ordinarily are bags. To keep the open ends distended and support the bags while receiving the grain, wire frames E are attached to the upper ends of the sides d of the platforms, over which the end of the bags may be stretched and retained by hooks e.

A grain-spout, F, of ordinary construction, designed to be connected with a thrashing-machine, has two branches, F', each of which terminates at a point directly above the platforms D. A cut-off, f, pivoted within the spout at the point of divergence of the branches

F', controls the discharge of grain through either branch, for the purpose presently described.

A register, G, of usual construction, is mounted on the upper portion of the frame, and a sliding pawl, g, working through a guide, g', actuates the registering mechanism. A vertically-pivoted lever, H, is connected at one end to the pawl g, and an arm, h, projects from its other or lower end through a slot in the side of the register's case. The upper edge of the partition A² has a notch or recess, a, formed therein, within which a rock-shaft, i, is journaled. Keyed to this shaft is a segment, I, and arm J. The latter projects vertically upward, and is slotted at j near its upper end, to receive the ends of the arm h and lever f', which project therethrough in opposite directions. The lever f' extends rearwardly from the pivotal center of the cut-off f.

From the sides d of the platform adjacent the partition A² are extended upward cords k, which connect with the opposite ends of the segment I.

In practice, it being desired to weigh off or measure a certain quantity of grain into separate parcels as it is delivered through the spout F, a counterpoise, K, of the requisite weight is adjusted on the arm of the yoke to a point representing the quantity of grain to be weighed. The bag or receptacle being in position under one of the spouts and the cut-off turned to one side or the other to shut off the branch F' not in use, as represented by dotted lines, Fig. 2, the grain will discharge into the receptacle till it overbalances the weight K, when the platform will descend, causing a corresponding elevation of the other, by reason of the segment I and cords k. Simultaneously with this movement of the platforms the arm J is vibrated, shifting the position of the cut-off, opening the branch F' previously closed, and shutting off that before opened, and at the same time giving an impulse to the pawl g, by which a register is made. While the grain is flowing through the branch now opened the filled receptacle is removed and an empty one put in its place. Thus no time is lost in weighing and packing, and a continued flow of grain is preserved through the spout.

The meter is automatic in its operation, and after being once set to weigh off a certain quantity of grain needs no further attention on the part of the attendant, save the removing of the filled receptacles and replacing the same by empty ones.

Having thus described my invention, what I claim, and desire to secure by Letters Patent, is—

1c. 1. The combination of the vertically-movable platforms, a segment pivotally supported above them, connections uniting the platforms with the opposite ends of the segment, an arm projecting from the axial line of the segment, 15 a bifurcated grain-spout, a pivoted cut-off located at the point of divergence of the spout, and a lever projected from said cut-off and engaged by said arm, whereby the vertical movements of the platforms will effect a simultaneous adjustment of the cut-off.

2. The combination, with the vertically-movable platforms, a pivoted segment, connections uniting the platforms with the opposite ends of the segment, a pivoted cut-off having a lever extending therefrom, and an arm projecting from the axial line of the segment and interlocking with said lever, of a register, a sliding pawl engaging its mechanism, a vertically-pivoted lever connected at its upper 25 end to the pawl, and an arm projecting later-

erally from its lower end and engaging the arm extending from the axial line of the segment, whereby said arm simultaneously actuates the register and cut-off, substantially as described, and for the purposes specified.

35

3. A grain-meter comprising the following elements in combination: a frame, a division-wall dividing the same into two compartments, a pair of levers pivoted to the sides of the compartments, yokes uniting the rear ends of each pair, and having rearwardly-projecting arms to receive counterpoises, platforms suspended from the front ends of each pair of levers, a segment pivoted in line with the division-wall, connections uniting the platforms with the segment, a slotted arm projected from the axial line of the segment, a register having an actuating-arm engaging the slot in said arm, and a bifurcated grain-spout provided with a pivoted cut-off having a rearward-projecting lever working in the slot in the said arm, the parts being constructed and operating in the manner substantially as hereinbefore specified.
